UNITED STATES PATENT OFFICE.

ENRICO BATTISTI, OF ROME, ITALY.

FASTENING DEVICE.

1,152,778.

Specification of Letters Patent. Patented Sept. 7, 1915.

Application filed August 13, 1913. Serial No. 784,563.

To all whom it may concern:

Be it known that I, ENRICO BATTISTI, a subject of the King of Italy, residing at Rome, in the Kingdom of Italy, have invented certain new and useful Improvements in Fastening Devices, of which the following is a specification, reference being had therein to the accompanying drawing.

The object of the present invention is a device by means of which the edges of any article may be rapidly and easily joined together, without the use of buttons, laces, buckles, eyelet-holes, clasps and the like. This fastening device has the advantage that the objects thus joined can be disconnected with equal facility and rapidity: it is applicable to any article, but is more specially adapted to dress articles, such as shoes, leggings, gloves, etc.

20 The device consists of three parts: two side pieces fastened to the borders of the ends to be joined together; and a third piece so arranged as to slide between the two former, which it thus holds together. It 25 will be understood that when the borders of an object are held together by this device, if the intermediate or locking piece is caused to slide in an opposite direction to that necessary for establishing the connection, 30 the borders of the said object are at once disconnected and rendered free.

In the annexed drawings Figure 1 shows in section and on enlarged scale one of the side pieces; Fig. 2 is a plan view of the 35 wire frame, which serves to form the side piece; Fig. 3 shows in section the three pieces connected, and Fig. 4 is a front view of a portion of the apparatus.

The drawings are all schematic and on a 40 variable scale.

An important characteristic feature of the apparatus consists in this, that all the parts of the device are flexible, being thus easily adaptable to any shape, however irregular, 45 which may be assumed by articles of dress.

The side pieces are provided with longitudinal grooves, and the middle piece has on its two edges the thickenings which have to run in the grooves.

50 Fig. 1 shows in cross section one of the side pieces according to the arrangement

now described, in which are used little hoops —1— wrapped from the inside and the outside by a ribbon —2— of leather, or of other suitable material, thus forming the laps 55 —3— in order to establish the connection with the border of the object. The canal —4— is thus formed for the purpose of receiving the sliding block of the middle part; for the passage of this sliding block the longitudinal cut —5— is left open.

The application of non contiguous hoops, at short distance one from the other, gives sufficient flexibility to the system; but this flexibility may likewise be obtained by the 65 use of a frame of metallic wire —6— first bent in the form of a Greek fret (Fig. 2) then curved so as to reproduce the shape of the above mentioned hoops —1— and covered in like manner.

As a result of the form of the side pieces as just described, the middle piece (Fig. 3) is conveniently made of a flexible connecting means —7— of suitable material, having on both its edges cylindrical thickenings of such 75 a diameter as to slide freely through the grooves —4— without any possibility of getting out of the opening —5—.

As connecting means may be employed a system of tie-bands —9— as that shown in 80 Fig. 4.

I claim:

Fastening device for flexibly joining the edges of articles of dress, such as shoes, 85 gloves and the like, comprising: a middle sliding piece with two lateral strings forming the edges of same, and two side pieces each of them formed by a metallic wire having the shape of a Greek fret and bent so as to form an incomplete cylindrical groove, 90 which leaves between its edges a longitudinal slit and is provided inside and outside with a flexible covering, in which grooves may slide the lateral strings of the middle piece.

95 In testimony whereof I affix my signature in presence of two witnesses.

ENRICO BATTISTI.
